TWO-ZONE PUMP

Temple P. Hoffer, Dallas, Tex., assignor to Otis Pressure Control, Inc., Dallas, Tex., a corporation of Delaware

Application October 11, 1948, Serial No. 53,965

17 Claims. (Cl. 103—4)

1

This invention relates to improvements in apparatus for pumping oil wells and refers more particularly to apparatus for pumping fluid from deep wells having two different zones of production.

This application is a continuation in part of my co-pending application for United States Letters Patent, Serial Number 702,769, filed October 11, 1946, for Two-Zone Pump, now U. S. Patent No. 2,513,869.

In the production of two-zone completion wells it is often desirable to be able to pump selectively from one of the production zones and not from the other. This is necessary, for instance, on some occasions in order to comply with the production laws of the various States where an allowable production from each of the production zones is fixed under the conservation laws. Then in production, if one of the zones produces its allowable production more quickly than the other zone, production from the zone that has produced its allowable production must be shut down while the balance of the allowable production of the other zone is produced. Also equipping the well with the pumping apparatus it is frequently necessary to land the upper pumping assembly and then release the assembly in order that the rod, which is to be used for the actuation of the pumping units, may be manipulated for the purpose of resetting a polish rod or the like. It is desirable to provide a releasable connection between the portion of the upper pumping unit that is supported on the actuating rod which connection will be remade when this portion of the pumping unit is released from its prior landing so that it may be reset by lowering the sucker rod.

This invention has for one of its objects the provision of two-zone pumping apparatus which may be employed to induce flow selectively from one of the production zones or from both zones simultaneously.

Another object of this invention is to provide two-zone pumping equipment which may be employed to pump from either of the production zones separately or from both of the production zones simultaneously.

A further object is to provide two-zone pumping equipment wherein manipulation of the actuating rod will render the pumping unit for one of the zones effective or ineffective as desired.

Still another object is to provide two-zone pumping equipment wherein rotative manipulation of the operating rod will render one pump unit operative or inoperative dependent on the rotational sense and wherein reciprocal longi-

2

tudinal movement of the actuating rod, outside the limits of the usual reciprocation for pumping purposes, will selectively render the other pumping unit operative or inoperative.

5 A still further object is to provide a two-zone pumping mechanism employing a standing-valve assembly carried by the actuating rod so as to be insertable and removable from the well tubing with the rod, the mechanism having a means for opening and closing the standing valve upon rotation of the actuating rod, dependent upon the rotational sense.

Yet another object is to provide two-zone pumping mechanism employing a pump barrel for one of the pump units which is mounted on the actuating rod and is insertable and removable from the well tubing along with the rod and wherein a latch mechanism is provided for securing the pump barrel in one of two positions within the well tubing so that with the barrel in one of such positions, the pump unit associated therewith will be effective and with the barrel in the other position, such pump unit will be ineffective.

15 20 25 Yet a further object is to provide reciprocating type pumping apparatus for installation in a two-zone completion well, the apparatus being capable of being rendered selectively effective or ineffective by manipulation of the actuating rod for the apparatus.

Even another object is to provide in two-zone pumping equipment a release mechanism for anchoring parts carried by the actuating rod in operative position within a string of flow tubing which parts may be selectively released and then remade without the necessity of pulling the parts to be anchored back to the ground surface after they have once been anchored in position.

Even a further object is to provide in two-zone pumping equipment a standing valve and packer assembly adapted to be inserted and withdrawn into and from a well tubing by the actuating rod for the pump, there being provided a first releasable latch mechanism for securing the assembly in operative position within the tubing and a second releasable latch mechanism for securing the assembly upon the rod wherein the first mechanism is active to release the second mechanism when the rod is moved downwardly in the tubing and wherein the second mechanism releases the first mechanism upon upward movement of the rod within the tubing.

Other and further objects of this invention will appear from the following description.

In the accompanying drawings which form a

part of the instant specification, are to be read in conjunction therewith and wherein like reference numerals are used to indicate like parts in the various views:

Fig. 1 is a schematic view partially in vertical section illustrating an oil well equipped with apparatus embodying this invention;

Fig. 2 is a vertical section upon an enlarged scale illustrating the part of the apparatus of Fig. 1 pertaining to the anchoring of a part of the upper pumping unit in a crossover flow device;

Fig. 3 is a view on an enlarged scale illustrating the lower pump unit in operative position;

Fig. 4 is a view similar to Fig. 3 but illustrating the lower pump unit in an inoperative position;

Fig. 5 is a view on an enlarged scale illustrating the standing valve of the upper pump unit together with a hold-down mechanism for closing the standing valve;

Fig. 6 is an elevational detail of the hold-down mechanism for the upper standing valve showing the same in half-section and upon a much larger scale than the showing of Fig. 5;

Fig. 7 is a view taken along the line 7-7 in Fig. 6 in the direction of the arrows;

Fig. 8 is a sectional view, upon an even larger scale, of the nut which secures the hold-down assembly to the standing valve assembly;

Fig. 9 is a view upon a greatly enlarged scale illustrating the locking or hold-down mechanism for securing the upper standing valve and packer in operative position and illustrating the parts just as the standing valve and packer assembly have been lowered to their operative position;

Fig. 10 is a view similar to Fig. 9 but showing the parts in operative position with the actuating rod also in operative position for pumping both of the zones of a two-zone well;

Fig. 11 is a fragmentary view similar to Figs. 9 and 10 but illustrating the parts in position with the standing valve packer assembly about to be withdrawn from the well tubing and with the hold-down mechanism or latch released.

Figs. 12 and 12A are enlarged views of the apparatus shown in Fig. 1; and Figs. 13 and 13A are enlarged views of the apparatus shown in Fig. 2.

Referring to Figs. 1, 12 and 12A well casing 15 has upper perforations 15a and lower perforations 15b adapted to communicate with upper and lower producing formations respectively of a two-zone producing well. Extending downwardly within the casing is a string of flow tubing 16 which is connected to special fittings and through these fittings extends to the lower formation. These special fittings house the upper and lower reciprocal-type pump units disposed respectively adjacent the upper and lower producing formations and this equipment will be hereinafter more fully explained.

Referring to the apparatus for pumping the upper producing formation, it is believed that an understanding of the apparatus will be obtained by first pointing out that the equipment for pumping the upper producing formation is of the reciprocal type and contains a standing valve, a plunger including a traveling valve, and a pump barrel, together with packing means for maintaining separate flow passages for the fluid produced from the two producing zones of the well.

While the pump barrel or liner for the upper pump unit is illustrated as having a stationary mounting on the tubing string so that it can be removed from the well only along with the

tubing string, it is, however, contemplated that this pump barrel may be mounted in a fashion to be removable with the actuating rod or sucker rod, which is connected to the pump plungers or pumping members. This latter type removable pump barrel is illustrated in conjunction with the lower pump unit.

In order to secure the upper pump barrel to the tubing a special coupling 17 is threaded to tubing 16 and has a threaded connection with an upper cylinder jacket 18. The lower end of jacket 18 is threaded to fitting 19. The coupling 17 and fitting 19 have confronting internal annular shoulders, 17a and 19a respectively, between which the pump barrel or liner 20 is secured.

Fitting 19 has a threaded connection not shown in the drawings with an upper packer sleeve 21 which carries a packing 22 providing a seal between the packing sleeve 21 and the tube 23. The tube 23 communicates with the interior of the pump liner 20, and provides a portion of the flow passage for conducting fluid from the upper formation to the ground surface. The fitting 24 is threaded to packing sleeve 21 and has a passage 24a therein which communicates between the tubing casing annulus and the annular space between tube 23 and the interior of fitting 24. This latter annular space and the passage 24a provide a portion of the passage for conducting well fluids produced from the lower formation into the tubing casing annulus in a manner to be hereinafter more fully explained. Fitting 24 has a threaded connection with an outer tubular member or packing mandrel 25 and the annular space between the mandrel and tube 23 provides a portion of the passage for the flow of fluid from the lower formation. The packing mandrel 25, carries externally thereof, annular packings 26 providing a seal between the casing 15 and the mandrel. These packings 26 may be of a conventional type, being supported on the mandrel 25 at an annular flange 25a provided intermediate the length of the mandrel.

This above packer arrangement has been found to be entirely satisfactory but as an alternative the packer arrangement shown and described in detail in my above-mentioned co-pending application, now U. S. Patent No. 2,513,869, may be employed.

The packing mandrel 25 is threaded to the outer casing 27 of a crossover flow device. Internally of the outer casing 27 is a flow member 28 (Fig. 2) which is threaded to the lower end of tube 23. This member 28 has peripheral grooves 28a therein extending axially and providing passages for flow of fluid into the annular space between tube 23 and mandrel 25. At circumferentially arranged positions, different than the positions of grooves 28a, member 28 is provided with ports 28b extending substantially radially and communicating with the upper ports 15a of the well casing and radial ports 27a in casing 27. With this arrangement the upper producing formation is in communication with the interior of the tubular flow member 28.

The flow member 28 has a threaded fitting with a cylindrical member 29 and concentrically arranged about the cylindrical member 29 is a casing 30. The space between the cylindrical member and casing 30 communicates with the passages provided by grooves 28a and provides a portion of the flow passage for the fluid from the lower producing formation of the well. The inner tubular or cylindrical member 29 is adapted to receive a packoff means to form a

seal between the actuating rod of the pumping equipment and the tube whereby the passageway for producing the well fluid from the upper formation is sealed off from the passageway for producing fluids from the lower formation.

The tube or cylindrical member 29 also carries latch parts in the form of a fitting 31 threaded thereto and having spring fingers 32 extending axially therefrom. This latch part is used to anchor a standing valve and packer assembly in operative position within the cylindrical member and is adapted for interlocking engagement with latch parts carried by the assembly. This assembly will be next described and then the locking of the assembly in place will be taken up.

The standing valve packer assembly is adapted to be mounted on a polish rod section 33 which makes up a part of the actuating rod for pumping the two pump units. The rod length 33 is connected to the lower end of pump plunger or pumping member 34 which in turn is connected to the sucker rod 35. The mounting of the standing valve packer assembly on the rod length 33 is such as to permit relative sliding movement between the rod and the assembly.

The standing valve is made up of a body part 36 having vertical passages 36a therein. The body 36 surrounds rod 33 and has a tapered seat surface 36b at its upper end in which the passages 36a terminate. This seat surface is tapered to receive the corresponding tapered surface upon an annular valve member 37 which has a sliding movement upon a guide extension 36c of the body member. The extension 36c is formed of spring fingers and is adapted to be connected to a movable stop to limit movement of valve member 37 as will be hereinafter more fully described.

The body 36 of the standing valve carries a packing 38 about its outer periphery which is held against a down-turned annular shoulder intermediate the ends of the body and a gland ring 39 which is threaded to the body. This packing preferably is of the chevron type and provides a seal between the valve body and the lower end of tube 23.

Obviously with the packing 38 sealing off between tube 23 and standing valve body 36, the only passage for fluid through the tubular passage leading to the flow tubing is through the vertical passages 36a of the standing valve body as controlled by valve member 37. Communicating with the vertical passage 36a and the upper producing formation are radial ports 39a in the gland ring 39. Thus flow may take place from the upper producing formation through the perforation 15a, ports 27a and 28b and 39a and thence through passages 36a.

In order to prevent intermingling of the fluids from the two producing formations it is necessary to pack off the interior of the cylindrical member made up of tubes 28 and 29 and forming a part of the crossover device. This latter may be accomplished by extending the valve body 36 downwardly to connect to a packing sleeve 40. This sleeve 40 is threaded to the lower end of the valve body 36. The packer sleeve 40 has disposed about its outer periphery packing 41 which may be of the chevron or the cup types and which is held in place upon the sleeve between a down-turned annular shoulder 40a and a gland ring or washer 42 which in turn is held upon the packer sleeve by retainer 43 threaded to the lower end of the sleeve. Retainer 43 carries internal packing 44 which also prefer-

ably is of the V-type. The packing 44 is retained within an enlarged diameter portion of the retainer 43 by the upper end of a latch part 45 threaded to the lower end of the retainer.

The latch part 45 is provided for the purpose of anchoring or securing the standing valve packer assembly in operative position to control the passageway through the tubular or cylindrical member 29 and carries an enlarged diameter portion 45a adapted to nest in the interlocking finger parts 32 which have internal recesses 32a formed therein for this purpose. The fingers 32 have a tapered portion 32b extending upwardly and outwardly from the recess 32a and downwardly and outwardly tapering surfaces 32c.

This locking or latch mechanism is detailed in Figs. 9, 10 and 11. With this arrangement it is clear that if means is provided upon the rod 33 for latching onto the assembly and pulling it downwardly within the tubing string and tubular parts 28 and 29, the enlarged portion 45a of the locking part 45 will first engage the tapered surfaces 32b on the fingers 32 spreading these fingers to an outward position. When the enlarged portion 45 reaches the recess 32a the parts will interlock to secure the standing valve packer assembly in operative position. However, it is then necessary to release the connection between the assembly and the rod 33 in order that the rod 33 may be reciprocated to actuate the pump units.

In my co-pending application mentioned above a shear set-screw was employed to secure the rod 33 to the standing valve packer assembly. While this arrangement was entirely satisfactory for certain purposes, it was not possible to re-engage the connection between the assembly and the rod without pulling the rod to the ground surface and resetting the set screw. In installing the apparatus in wells it is often desirable to release the standing valve packer assembly from operative locked position to permit manipulation of the actuating rod for purposes of setting a polish rod at the ground surface or the like and then pass the actuating rod downwardly again into a position to reseat the standing valve and packer assembly.

If it is necessary to pull the entire length of actuating rod it is a very expensive and time-consuming operation. In accordance with this invention there has been provided a releasable set of locking elements between the actuating rod and the standing valve packer assembly. These interlocking latch elements include an internal recess 45b in the part 45 secured to the assembly, having an abrupt or sharp inturned flange portion adjacent its end, providing a locking surface 45c. The rod carries cooperating or co-acting locking latch elements in the form of fingers 46 secured to coupling member 47. Coupling member 47 has opposed end sockets for receiving ends of adjacent sections of the actuating rod.

The fingers 46 have at their ends out-turned lugs 46a with hook surfaces adapted to engage surface 45c in order to pull the assembly downwardly within the string of tubing along with the lowering of the rod. In order to release these fingers when the standing valve packer assembly has been landed in operative position, the fingers 46 are provided with tapered surfaces 46b. The inherent resiliency of the spring fingers 32 is much stronger than is that of the spring fingers 46 and when the enlarged portion 45a is nested in the recesses 32a the tapered surfaces 32c upon

the fingers 32 engage the surfaces 46b to collapse the locking elements inwardly sufficiently to provide for clearance between lug 46a and shoulder 45c. This particular position of the parts is shown in Fig. 9. Further downward movement of actuating rod 33 will release the interlocking elements 45b and 46, as shown in Fig. 10.

It is then necessary to provide parts carried by the actuating rod for engagement with the fingers 32 to release them from interlocking engagement with the enlarged portion 45a upon upward movement of the rod. This may be accomplished by providing large diameter parts 46c upon the fingers 46 which are adapted upon upward movement of the rod to engage the tapered portions 32c to expand fingers 32 to the position shown in Fig. 11 where the enlarged portion 45a is free to be released from the recesses 32a. This expansion of the fingers 32 will take place because the fingers 46 will be collapsed into abutment with the rod as shown in Fig. 11 preventing further inward collapsing of these fingers whereby with this support they are strong enough to spread the fingers 32 outwardly. It is preferable to provide a rounded shoulder 45d upon the upper edge of the enlargement 45a which will abut a tapered shoulder 32d carried by the spring fingers in the event of any engagement between the fingers and the enlargement as the enlargement is removed upwardly from the recess 32a.

Referring now to Figs. 6, 7 and 8, the hold-down mechanism for securing valve member 37 of the standing valve in closed position to render the upper pump unit ineffective, will be explained. This releasable hold-down for the valve member 37 is manipulatable by rotation of the actuating rod string. It is therefore necessary to provide a movable stop carried by the standing valve assembly and a wrench mechanism between the stop and the actuating rod for selectively raising and lowering the stop.

This may be accomplished by providing a tubular stop member 48 having an internal threaded portion receiving a nut 49 threaded therein. Preferably the threads between the nut and stop are heavy fast-lead Acme-type threads which will turn easily as compared to the threaded connection employed in making up the usual actuating or sucker rod. This nut 49 has an annular recess in its inner periphery shown at 49a which receives the enlarged end portions of spring extension members 36c. The upper ends of these members 36c have lugs 36d adapted to mate with the openings between lugs 49a on nut 49 to hold the nut 49 against rotation with stop 48 whereby rotation of the stop will raise or lower the nut within the stop dependent upon the direction of rotation.

The stop 48 has a telescoping clutch engagement with a wrench element 50 having a non-circular outer configuration which may be octagonal or the like. The upper end of stop 48 is serrated and the ends of the members have in-turned flanges having flat inner peripheral surfaces as shown in Fig. 7. With this telescoping engagement, the non-circular clutch parts prevent rotation between the members 48 and 50. The wrench part 50 carries at its upper end wrench elements 50a adapted to mate with recesses formed in a special coupling 51 included in the actuating rod string. This coupling is shown in Fig. 5, and preferably constitutes the connection between the lower portion of the rod

and the pump plunger 34. At the lower end the coupling 51 has cut-away wrench portion or recesses adapted to mate with the upstanding lugs 50a formed on wrench part 50. The ports 51a communicate exteriorly of the coupling and interiorly of the pump plunger. The external threaded periphery of the upper end of the coupling is adapted to be threaded to the lower end of the pump plunger 34.

With the above arrangement it is believed clear that with the standing valve packing assembly in operative position and with the latching elements 45 and 46 between the actuating rod and assembly released, the actuating rod may be lowered until coupling 51 engages wrench part 50 with lugs 50a mated in the sockets formed in the lower end of the coupling. Then rotation of the actuating rod will impart rotation to the telescoping parts 48 and 50 and inasmuch as nut 49 is held against rotation with the stop 48 the nut will be raised or lowered relative to the stop dependent on the direction of rotation. If the rotation is such as to move the stop downwardly the lower end of the stop will abut the upper end of valve member 37 and force it into seated position against the seat formed on the standing valve body 36. When it is desired to release the valve member 37, reversed rotation of the actuating rod with the parts 50 and 51 engaged will effect a raising of the stop 48 relative to the valve member whereby the valve member will be free to slide upwardly and downwardly upon the guide 36c to serve as a check valve to control back flow through the standing valve.

In order to hold the lugs 50a in engagement with the wrench part of coupling 51 it is preferable to provide a spring or resilient member 52 internally of the telescoping parts 48 and 50. This spring may have one end abutting against an annular down-turned shoulder 50b formed upon the part 50 and its other end abutting against the upper end of nut 49. This spring is in compression and urges the two telescoping parts toward extended position.

Thus there is provided a movable part associated with the upper pump unit for selectively rendering this unit operative and inoperative upon movement of the part. In addition, there is provided a lost motion connection between the part and the actuating rod which permits normal pumping reciprocation of the rod without operative movement of the movable part and which operatively moves the part upon a movement of the rod in other than its normal pumping reciprocation.

The plunger 34 heretofore referred to is carried at the lower end of the string of rods 35 and is shown somewhat schematically in the drawings. For more detailed description, the co-pending application mentioned above, now U. S. Patent No. 2,513,869 may be referred to. The plunger comprises a hollow tubing 34 having a snug fit within linear or pump barrel 20 and carries a traveling valve shown schematically at 53. The valve cage of the traveling valve has radial ports 53a which provide communication between the interior of tubing 16 and the interior of the plunger 34. This completes the passage to the ground surface for well fluids produced from the upper producing zone.

Turning now to the pump units for the lower formation, this is shown in Figs. 1, 3 and 4. The outer casing 30 is connected at its lower end with an adapter 54 which is connected to a continuation of the string of tubing 16 thereby providing

communication between the interior of casing 30 and the lower producing formation. There is provided a packer 55, which may be of any suitable construction, between the tubing 16 and casing 15. This packer and packer 26, provides a sealed off portion of the tubing casing annulus communicating with the upper producing formation.

Near its lower end the string of tubing 16 carries a landing shoe 56. This landing shoe may be threadedly or otherwise secured to the tubing and has a tapered seating or landing surface 56a at its upper end. This tapered seating surface is adapted to sealingly receive a correspondingly tapered seating surface or part carried by the lower pump unit. The shoe 56 has a passageway therethrough and contains a recess 56b adapted to receive a latch element carried by the lower pump unit. The shoe also has an internal shoulder 56c adapted to be engaged by latch elements carried by the lower pump unit to secure it in a second position relative thereto.

The lower pump unit comprises a barrel portion 57 having a sliding guide connection at its upper end with the actuating rod. This guide connection has ports 57a communicating between the interior of the pump barrel and the interior of tubing 16. At the lower end barrel 57 is connected to a standing valve or seating part 58 having a lower seating surface 58a, a central passageway and a seat surface 58b at the upper end adapted to seat a ball check valve 59. Within the pump barrel is mounted a plunger, including a pump member 60 mounted on the lower end of actuating rod 35 which extends within the pump barrel, and a traveling valve. Cage 61 is secured to the lower end of the plunger. Passages in the ends of the plunger place the interior thereof in communication with the interior of the pump barrel.

The seating part 58 carries latching members 62 in the form of spring elements having outwardly tapered lugs with shoulders 62a and 62b. These lugs are adapted to engage the shoe at two different locking positions shown in Figs. 3 and 4 respectively. In the Fig. 3 position with the shoulder 62a engaging shoulder 56c of the shoe, the tapered surface 58a sealingly seats on the tapered surface 56a of the shoe. In this position the lower pump unit is operatively mounted and will induce flow of well fluid from the lower formation when the plunger is reciprocated within the pump barrel 57. However, by lifting up on the actuating rod 35 until the upper end of the plunger engages the guide at the upper end of the pump barrel, the plunger will be elevated to release the element 62 from the Fig. 3 position and the lugs of the latching members 62 will then lodge in the recess 56b as shown in Fig. 4. In this position the lower pump unit is mounted in a fairly stable position but reciprocation of the pump plunger will not induce flow from the lower formation because the fluid will by-pass through the upper ports 57a of the pump barrel, between the pump barrel and tubing 16 and through the central passage of the standing valve member 58. Thus in the Fig. 4 position the pump will be ineffective to pump the lower formation and the arrangement is such that the pump may be selectively locked in either operative or ineffective pumping position.

Thus there has been provided a movable part associated with the lower pump unit for selectively rendering it operative and inoperative upon movement of the part and a lost motion con-

nexion between the part and the rod permitting normal pumping reciprocation of the rod without operative movement of the part and operatively moving the part upon a movement of the rod in other than its normal pumping reciprocation.

It is believed that the operation of the pump is apparent from the foregoing description. The string of tubing with the crossover flow mechanism mounted therein and with the landing shoe 56 secured near the lower end thereof is mounted in the well casing with the packers 26 and 55 separating the casing tubing annulus into upper, lower and intermediate chambers. The actuating rod 35 is then made up with plunger 60 secured to the lower end thereof and residing within the pump barrel 57. This is then lowered into the tubing string 16 and as the rod is made up the coupling 47 carrying releasable latch elements 46 is secured therein and connected to rod 33 which has mounted thereon the standing valve packer assembly for the upper pump unit. This is all assembled on the rod string with the interlocking elements 46 of the coupling member 47 locked in position within the recess 45b. This section of the rod is then lowered into the well tubing and in proper position there is secured to the rod the special coupling 51 which will serve as the wrench unit for actuating the hold-down mechanism to close off the upper standing valve member 37. Pump plunger 34 is then secured to the fitting 51 and the traveling valve 53 connects the lower end of the sucker rod 35 with the plunger.

With all this equipment mounted on the rod the rod is then lowered into the tubing 16 until the interlocking latch parts 45 carried by the upper standing valve packer assembly engage with the interlocking latch parts 32 carried by the cylindrical member 29 constituting a part of the crossover flow device. By referring to Fig. 9 it will be seen that when the enlarged portion 45a seats in the recess 32a the relatively stiff fingers 32 have their tapered surface 32c engaged with the tapered surface 46b of the interlocking latching elements carried by the rod. These relatively stronger fingers collapse the elements 46a releasing the latch between the assembly and the rod. The actuating rod is then lowered until the seating part 58a engages the seating shoe 56. Sufficient weight is placed on the rod assembly to force the latching elements 62 into their Fig. 3 position.

The actuating rod is then raised somewhat to place the pump plungers 34 and 60 in operative position relative to the upper and lower pump barrels respectively. Reciprocation of the rod will induce flow from both the upper and lower formation. The well fluids produced from the lower formation will pass upwardly through the lower pump unit, through the lower portion of tubing 16, through the annular space between the cylindrical parts 30 and 29, upwardly through passages 28a and 24a and into the casing tubing annulus above the packers 26. The fluid is then produced through this annulus to the ground surface. It is contemplated that this fluid could be produced through an auxiliary tubing string lodged in this annulus.

Flow from the upper producing formation enters the casing through perforations 15a and is retained in the casing between the packers 26 and 55. The fluid, upon actuation of the upper pump unit, will then enter through the ports 27a, 28b and 39a into the interior of the stand-

ing valve body. The fluid will then pass upwardly through passages 36a in the standing valve body and when the valve 37 is free to rise upwardly upon the guides 36c the fluid will force the valve out of position, blocking the passages 36a, and will then enter into the liner or pump barrel 20. Of course this latter movement will take place when the plunger is moving upwardly and when the plunger 34 is moving downwardly the valve member 37 will prevent back flow of fluid 10 from the liner. The traveling valve 53 serves in its usual function to raise the fluid upon the upstroke of the plunger. The fluid is then transferred to the ground surface through the tubing string 16.

If, during the landing operation for installing the two pump units in the well equipment, it becomes necessary to dislodge the upper standing valve packer assembly from operative position for any reason, this may be readily accomplished by raising the actuating rod until elements 46 are collapsed and enter into the recess within the enlarged portion 45a of the locking part carried by the standing valve packer assembly. The tapered surfaces 32c of the locking parts carried by the cylindrical member 29 will first engage the tapered ends of lug 46a and then the tapered surfaces 46b to collapse elements 46. However, they can not collapse further after engagement with the rod and further raising of the rod will bring the surfaces 46c into contact with the tapered ends of members 32 to spring them outwardly as shown in Fig. 11 to release the locking parts between the standing valve packing assembly and the cylindrical member 29. Further movement upwardly of the rod will carry the assembly upwardly and the members 46 will expand outwardly to engage the interlocking element carried by the packing standing valve assembly as soon as the shoulders 46c are brought out of engagement with the relatively stiff elements of the locking parts 32. Thus when it is again desired to land the assembly in operative position, lowering of the actuating rod will pull the standing valve packer assembly into locked position ready for operation.

If it becomes desirable to produce only from the lower formation and to render the upper pumping unit ineffective this may be accomplished by lowering the actuating rod 35 until coupling member 51 engages with wrench part 50a carried by part 50. Then rotation of the rod in a clock-wise direction when looking down on the rod will raise nut 49 relative to the stop 48 and the stop 48 will be moved into engagement with valve member 37 to hold it seated and thus close off all flow through the standing valve. This renders this upper pump unit ineffective. Reverse rotation of the rod with the 60 coupling 51 engaged with the member 50 will back the stop off so as to again render the upper pump unit operative.

When it is desirable to produce only from the upper producing formation, the lower pump unit may be rendered ineffective by picking up on the actuating rod 35 until the upper end of the plunger engages the guide part of the barrel 57. Then by pulling on the actuating rod the spring members 62 will be pulled into the recess 56b. This anchors this lower pump assembly in a relatively stationary position but breaks the seal between the seating surfaces 58a and 56a. The actuating rod is then lowered somewhat 65 into position for reciprocation and only the upper

pump unit will be effective due to the bypassing of fluid about the lower pump unit. This unit may be selectively rendered operative by lowering the actuating rod until the lower end of the pump plunger engages the standing valve ball member 59. The weight of the rod will then cause the pump barrel 57 to be forced to its lower or Fig. 3 position with a seal formed between the tapered seating surfaces 56a and 58a.

It will be seen that the objects of this invention have been accomplished. There has been provided two-zone pump apparatus which is capable of selectively pumping either of the upper or lower producing zones simultaneously or separately. The construction is such that all the operating parts for the pumps, for both upper and lower producing zones, may be carried by the actuating rod and selectively landed or released from operative position by manipulation of the rod. The arrangement is such that one of the pump units may be rendered effective or ineffective by selected rotative manipulation of the actuating rod for the two pump units and the other pump unit may be rendered selectively operative or ineffective by reciprocal manipulation of the actuating rod without the limits of the normal pumping reciprocation. The apparatus is such that the production from each of the producing zones is conducted to the ground surfaces through separate flow passages preventing intermingling of the fluids from the two zones.

From the foregoing it will be seen that this invention is one well adapted to attain all the ends and objects hereinabove set forth, together with other advantages which are obvious and which are inherent to the structure.

It will be understood that certain features and sub-combinations are of utility and may be employed without reference to other features and sub-combinations. This is contemplated by and is within the scope of the claims.

Referring to the appended claims and to the terminology used therein, it is to be understood that the standard valve and packer assembly made up of body part 36 and other parts, the valve member or movable means 37, the stop member or movable part 48, as well as elements represented by numerals 50, 52 and other elements cooperating with the named parts, form a part of the first pump unit, all of these elements being shown generally in Figure 12. Further, in this same connection, the lower pump barrel 57 and latching members 62 and generally the parts shown in Figures 3, 4 and 12A form a part of the second pump unit.

As many possible embodiments may be made of the invention without departing from the scope thereof, it is to be understood that all matter herein set forth or shown in the accompanying drawings is to be interpreted as illustrative and not in a limiting sense.

Having described the invention, what is claimed is:

1. In two-zone well pumping apparatus for use in pumping wells having two vertically spaced fluid-producing formations, communicating with a well bore, said apparatus including in combination a string of flow tubing extending downwardly within the well bore and having openings to place its interior in communication with both formations, two reciprocating-type pump units disposed within the tubing adjacent the two formations respectively, said units having pump barrels, pump members and standing and travelling valves ar-

ranged in a conventional manner, a single actuating rod operably connected with both pump units, and means including a movable part for selectively and releasably closing one of the standing valves, a releasable connection between said means and said actuating rod for moving said part upon rotation of the rod with the connection made.

2. In two-zone well pumping apparatus for use in pumping wells having two vertically spaced fluid-producing formations communicating with a well bore, said apparatus including in combination a string of flow tubing extending downwardly within the well bore and having openings to place its interior in communication with both formations, two reciprocating-type pump units disposed within the tubing adjacent the two formations respectively, said units having pump barrels, pump members and standing and travelling valves arranged in a conventional manner, a single actuating rod operably connected with both pump units, a stop carried by the standing valve of one pump unit adapted upon rotation in one direction to be advanced into engagement with the valve member of last said standing valve to hold it closed and upon rotation in the other direction to be moved to an out-of-the-way position to permit the valve member to move to an open position, and releasable interlocking parts carried by the stop and rod adapted upon engagement and rotation of the rod to rotate the stop.

3. Apparatus as in claim 2, wherein said standing valve of said one pump is of the annular type.

4. In pumping apparatus for use in pumping wells having two vertically spaced fluid-producing formations communicating with the well bore, said apparatus including in combination a string of flow tubing extending downwardly within the well bore and having openings to place its interior in communication with both formations, two reciprocating-type pump units disposed within the tubing adjacent the two formations respectively, said units having pump barrels, pump members and standing and travelling valves arranged in a conventional manner, a seating shoe carried by the tubing string adjacent one producing formation, the pump barrel of one of the pump units constituting a cylindrical element communicating at both ends with the interior of the tubing string, one of the standing valves carried by the lower end of the cylindrical element to control flow therethrough, a part on the cylindrical element adapted to be sealingly seated on the seating shoe and a latch mechanism including engageable parts carried by the cylindrical element and by the tubing string to releasably secure the cylindrical element in seated and non-seated relationship with the seating shoe.

5. In apparatus for use in pumping wells having two vertically spaced fluid-producing formations communicating with the well bore, said apparatus including in combination a string of flow tubing extending downwardly within the well bore and having openings to place its interior in communication with both formations, two reciprocating-type pump units disposed within the tubing adjacent the two formations respectively, a common actuating rod for said pump units, said units having pump barrels, pump members and standing and travelling valves arranged in a conventional manner, a seating surface carried by the tubing string adjacent one producing formation, the pump barrel of one of the pump units comprising a cylindrical element communicating

at both ends with the interior of the tubing string, one of the standing valves carried by the lower end of the cylindrical element to control flow therethrough, a seating part on the cylindrical element adapted to be sealingly seated on the seating surface, a latch mechanism including engageable parts respectively carried by the cylindrical element and by the tubing string to releasably secure the cylindrical element in seated and non-seated relationship with the seating surface, and parts carried by the actuating rod and cylindrical element adapted to engage upon reciprocation of the rod outside the usual limits of a pumping operation to move the cylindrical element within the tubing string to manipulate the latch mechanism.

6. As a sub-combination, apparatus for use with equipment for pumping from two vertically spaced production zones in a well comprising a seating shoe adapted to be connected into a tubing string and having a seat surface thereon, a cylindrical element including a pump barrel with a passageway therethrough and a seat part carried by said element adapted to sealingly engage the seat surface of said shoe, and a latch mechanism including a part carried by said element, said mechanism being adapted to releasably secure the cylindrical element in two selected positions relative to the shoe, the positions being with the seat part seated upon and unseated from the seat surface.

7. As a sub-combination, apparatus for use with equipment for pumping from two vertically spaced production zones in a well comprising a seating shoe adapted to be connected into a tubing string and having a seat surface thereon; a cylindrical element including a pump barrel with a passageway therethrough, a seat part carried by said element adapted to sealingly engage the seat surface of said shoe, and a standing valve controlling the passageway; and a latch mechanism including a part carried by said element; said mechanism being adapted to releasably secure the cylindrical element in two selected positions relative to the shoe, the positions being with the seat part seated upon and unseated from the seat surface.

8. In apparatus for pumping wells having two vertically spaced production zones and equipped with a string of well casing and a string of flow tubing, the latter having openings to place its interior in communication with two vertically spaced producing formations, said apparatus including upper and lower pump cylinders disposed in the tubing string adjacent the respective producing formations and providing a part of the passageway through said tubing, pump members reciprocally mounted in the cylinders with a common actuating rod interconnecting them, and a standing valve and packer assembly carried by the rod and insertable and removable therewith into and out of the tubing, the packer adapted to seal off the passageway between the standing valve and the lower formation, the improvement which resides in the combination therewith of latch mechanism for releasably securing the assembly in operative position comprising coacting latch parts carried by the assembly and tubing string adapted to engage upon movement of the assembly into operative position relative to the tubing to releasably anchor the assembly, releasably engageable latch elements carried by the rod and assembly, a part carried by the tubing for releasing said latch elements when the assembly is anchored, and a part carried by the rod adapt-

ed to release the latch parts when the rod is withdrawn from the string of tubing.

9. In apparatus for pumping wells having two vertically spaced production zones and equipped with a string of well casing, a string of flow tubing extending to the lower producing zone and having openings to place its interior in communication with both zones, said apparatus including two reciprocating-type pump units, with a common actuating rod, disposed within the tubing adjacent the two producing zones respectively; one of the pump units including a standing valve and packer assembly slidably mounted upon and surrounding the actuating rod and adapted to be lowered into and withdrawn from the tubing string with said rod, the standing valve having a passage therethrough communicating with one of the zones and adapted to control flow therefrom, the packer adapted to divide the tubing to separate the portions thereof communicating with the two zones, a hold-down mechanism for releasably anchoring the assembly in operative position relative to said one pump unit including interlocking parts carried by the assembly and tubing adapted to be releasably engaged and anchor the assembly, and interlocking elements carried by the assembly and rod adapted to releasably secure the assembly against sliding on the rod, and means carried by the interlocking parts and elements respectively adapted to co-act with each other whereby the elements are released upon downward travel of the assembly into position to lock the parts and the parts are released upon upward travel of the rod to engage the interlocking elements.

10. As a sub-combination, reciprocating-type pump apparatus adaptable for use in conjunction with well production apparatus for pumping from a plurality of vertically spaced production zones in a well comprising a cylindrical member adapted to be disposed within a string of flow tubing to receive a standing valve and packer, a rod adapted to be connected as a part of an actuator for reciprocating a pump member, a standing valve and packer assembly slidably mounted on said rod, interlocking latch parts carried by the cylindrical member and assembly adapted when interlocked to anchor the assembly, interlocking latch elements carried by the assembly and rod adapted to releasably secure the assembly against sliding on the rod, and means carried by the interlocking parts and elements respectively adapted to co-act with each other whereby the elements are unlocked upon downward travel of the assembly into position to lock the parts and the parts are unlocked upon upward travel of the rod to lock the interlocking elements.

11. As a sub-combination, reciprocating-type pump apparatus adaptable for use in conjunction with well production apparatus for pumping from a plurality of vertically spaced production zones in a well comprising a cylindrical member adapted to be disposed within a string of flow tubing to receive a standing valve and packer, a rod within said cylindrical member and adapted to be connected as a part of an actuator for a reciprocating pump, a standing valve and packer assembly slidably mounted on said rod, interlocking latch parts carried by the cylindrical member and assembly adapted to releasably engage each other to anchor the assembly, and interlocking latch elements carried by the assembly and rod adapted to releasably secure the assembly against sliding on the rod, surfaces on the latch parts carried by the cylindrical member adapted to engage

peripheral parts on the latch elements carried by the rod to release same when the latch parts of the assembly are drawn into engagement with the cylindrical member latch parts on lowering of the rod, and other peripheral portions on the rod latch elements adapted to engage surfaces on the cylindrical member latch parts to release same when the rod is raised to re-engage the latch elements.

10 12. As a sub-combination, reciprocating-type pump apparatus adaptable for use in conjunction with well production apparatus for pumping from a plurality of vertically spaced production zones in a well comprising a cylindrical member adapted to be disposed within a string of flow tubing to receive a standing valve and packer, a reciprocative rod within the cylindrical member, a standing valve and packer assembly slidably mounted on said rod within said cylindrical member, spring fingers carried by the cylindrical member and extending axially thereof, said fingers formed with an annular internal recess adjacent their ends, and having internal beveled surfaces at their ends, a latch extension secured to the assembly and having an exterior annular enlargement at its end adapted to nest in the recess of the spring fingers to releasably anchor the assembly to the cylindrical member, said extension having an internal annular recess with an annular opening thereto at the end of the extension and between the extension and rod, spring latch elements secured to the rod and extending axially thereof with out-turned lugs at the ends 25 for engaging the extension recess to releasably secure the assembly against sliding on the rod, the latch elements being weaker than the spring fingers and having parts engageable thereby to release the assembly when the extension enlargement is nested in the spring fingers recess and having other parts adapted to engage the beveled ends of the spring fingers to spread same and thereby release the enlarged end of the extension when the rod is raised.

45 13. In a two-zone well pumping apparatus for use in pumping wells having two vertically spaced fluid-producing formations communicating with a well bore, said apparatus including in combination, a flow string of tubing extending downwardly within the well bore and having openings 50 to place its interior in communication with both formations, first and second reciprocating-type pump units disposed within the tubing adjacent the two formations respectively, a single actuating rod operably connected with both pump units, a closable standing valve assembly associated with said first pump unit comprising a body, a valve member movable relative to said body, a stop carried by the body and movable relative to the body upon rotation to limit movement of the valve member, a part carried by said stop adapted to be engaged by a co-acting wrench part carried by said rod, a valve assembly associated with said second pump unit comprising a seating shoe disposed within the tubing string, a valve element carried by the second pump unit adapted to be sealingly seated on the seating shoe and a latch mechanism carried by the second pump unit and tubing string to releasably secure the valve element in seated and non-seated relationship with the shoe.

60 14. In two-zone well pumping apparatus for use in pumping wells having two vertically spaced fluid-producing formations communicating with a well bore, said apparatus including in combina-

tion a flow string of tubing extending downwardly within the well bore and having openings to place its interior in communication with both formations, first and second reciprocating-type pump units disposed within the tubing adjacent the two formations respectively, a single actuating rod operably connected with both pump units, a closable standing valve assembly associated with said first pump unit comprising a body member with port means therethrough, a valve member having a movable mounting relative to the body member and movable into open and closed positions relative to the port means to control flow therethrough, a stop carried by the body member to limit movement of the valve member, the mounting of the stop being such as to cause it to move toward and away from the port means upon relative rotation of the stop and body member, the direction of movement depending upon the rotational sense, and a part carried by said stop adapted to be releasably engaged by a co-acting wrench part carried by said actuating rod, said second pump unit comprising a seating shoe adapted to be connected to the tubing string and having a seat surface thereon, a cylindrical element including a pump barrel with a passageway therethrough and a seat part adapted to sealingly engage the seat surface of said shoe, and latch mechanism between the cylindrical element and the tubing string adapted to releasably secure the cylindrical element in two selected positions relative to the shoe, the positions being with the seat part and seat surface seated and unseated.

15. In a two-zone well pumping apparatus for use in pumping wells having two vertically spaced fluid-producing formations communicating with a well bore, said apparatus including in combination, a flow string of tubing extending downwardly within the well bore and having at least one opening for each formation to provide communication between the interior of the tubing and both formations, means within the tubing communicating with each of said tubing openings, two reciprocating type pump units disposed within the tubing adjacent the two formations respectively, an actuating rod operably connected with both pump units, first additional means rendering one of said pump units inoperable upon rotation of said rod and including a first part having an operating connection with the rod and said first part being movable relative to the tubing by rotation of the rod and cooperating with the communicating means within the tubing, to interrupt normal fluid flow through the communicating means and from said one pump unit, and second additional means rendering the other

5 of said pump units inoperable upon reciprocation of said rod outside the usual limits of a pumping operation and including a second part having an operating connection with the rod and movable relative to the tubing to cooperate with said communicating means to interrupt normal fluid flow through said communicating means and from said other pump unit.

16. A pumping apparatus which comprises, in combination, a tubing, first and second reciprocating type pump units arranged in tandem in said tubing, a reciprocative actuating rod connecting said pump units for operation thereof, movable means having an operating connection with said rod and cooperating with means forming a part of said first pump unit selectively rendering said first unit operative and inoperative upon movement of said movable means, and a lost motion connecting means between said movable means and said rod providing normal pumping reciprocation of said rod without operative movement of said movable means and operatively moving said movable means upon a movement of said rod in other than said normal pumping reciprocation and on an axis extending longitudinally with respect to the tubing axis.

20 17. The apparatus of claim 16 in combination with second movable means having an operating connection with said rod and cooperating with means forming a part of said second pump unit for selectively rendering said second unit operative and inoperative upon movement of said second movable means, and a second lost motion connecting means between said second movable means and said rod permitting normal pumping reciprocation of said rod without operative movement of said second movable means and operatively moving said second movable means upon a movement of said rod in other than said normal pumping reciprocation and on an axis extending longitudinally with respect to the tubing axis.
